UNITED STATES PATENT OFFICE.

HARRY B. SNELL, OF BUFFALO, NEW YORK, ASSIGNOR TO CURTISS AEROPLANE AND MOTOR CORPORATION, A CORPORATION OF NEW YORK.

WIRE-BENDING MACHINE.

1,316,257.

Specification of Letters Patent. Patented Sept. 16, 1919.

Application filed May 18, 1916. Serial No. 98,344.

To all whom it may concern:

Be it known that I, HARRY B. SNELL, a citizen of the United States, residing at Buffalo, in the county of Erie and State of New York, have invented certain new and useful Improvements in Wire-Bending Machines, of which the following is a specification.

My invention relates to aircraft factory equipment and more particularly to wire bending machines which first indent and subsequently bend or loop the wire to an extent determined by previous adjustment of the machine. The characteristic of the invention is the use of an abutment and a lever on the one hand and a mandrel and a lever on the other; the levers, in the bending of the wire, being moved in sequence so that the indenture will first be made, with the loop immediately following. In the manufacture of aeroplanes a large quantity of high grade wire is used; piano wire being preferred. Such wire, by reason of its grade and high resiliency cannot, except with difficulty, be bent or shaped without the use of appropriate wire bending or wire forming machines. By the present invention it is proposed to so construct the wire bending machine and so arrange the various levers and abutments that one or more loops or eyes of a given size and form may be separately formed in piano wire through movement of the levers independently. Furthermore, adequate provision is made for such adjustment as will enable wires of different gage and loops of different size to be respectively worked and formed.

Of the drawings,

Figure 1 is a perspective view of the wire bending device or machine,

Figs. 2 and 3 illustrate in plan the various positions assumed by the levers in bending the wire,

Fig. 4 is a section on the line 4—4 of Fig. 2, Fig. 5 is a fragmentary view illustrating partly in section and partly in elevation the ratchet adjusting means, and

Fig. 6 is a plan view of a modified type of machine.

By way of example the various elements of the machine are shown as mounted upon a bed or table 1 of a given form. The size and form of this table is immaterial. Upon it is mounted a plate 2 having one end cut away as at 3 and 4, adjacent which end and

upon the plate an abutment 7 is formed. This abutment, together with lever 6, constitutes the indenture forming means. Said lever is pivoted at one side of the abutment 7 as at 10 and equipped at its pivoted end 60 with a dog 8 of substantially diamond shape. This dog is centrally recessed as at 12 to accommodate that portion of the lever 6 over which it is fitted. The pivot 10 not only affords an axis about which the lever is 65 moved but also a fastening means, together with pins 9, for removably fastening the dog in place. From the pivot 10 to the remote dog extremities the distance is at variance. Either end of the dog, according to 70 its placement with respect to the lever 6, may be used as the wire engaging end and indenture forming element of the device. The end 11 in Fig. 1, however, is shown as the active end. By placing the short end of 75 the dog toward the abutment 7, wire of larger size can be bent. At the end of the table 1 and slightly removed from the end of the plate 2, a mandrel, designated in its entirety by the numeral 13 is disposed. This 80 mandrel (see Fig. 4) is of a construction such that loops of different size may be formed by bending the wire around it. To this end it is made small at 14 and large at 15. Further adjustment may be made 85 if desired. An exteriorly threaded bearing 21 integral with the lever 5 is used as a guide for the mandrel 13 and as a bearing for said lever. It is provided with an enlarged end and a shank, the former engaging the top 90 surface of the bed or table 1 and the latter in an opening to extend beneath the table where it is locked, or rather fastened, by means of a nut or equivalent means.

The end of the mandrel remote from that 95 portion acting as a lug about which the wire is looped, is extended as at 20. To this extended end a lever 22 is pivoted as at 24. This lever, intermediate its ends, is fulcrumed and at its opposite end pivoted to 100 an adjusting ratchet 25 having its upper portion extended above the table 1 through an opening 27. The teeth 26 of the ratchet engage the table at a point 28 and by this engagement lock the mandrel against vertical 105 play. The support for the lever 22 is indicated at 23.

For coöperation with the mandrel 13 a lever 5 and dog 16 are provided. The lever 5 is pivoted with the mandrel acting as a 110

pivot. This is possible and in fact desirable since the axis of the mandrel and the axis about which the lever pivots should coincide. The dog 16 is of substantially the same type or form as the dog 8 of the lever 6. Its size, at opposite sides of its center point is at variance. Accordingly either end may be brought into contact with the wire, although the end 18 is shown in Fig. 1 as active. The dog is removably fastened to the lever 5 as indicated at 18'.

In operation, the wire, indicated 19, is laid between the abutment 7 and the dog 8 on the one hand and the mandrel 13 and 15 dog 16 on the other, with the levers 6 and 5 respectively in engagement with a stop 29 and at right angles to the wire 19. By slightly moving the lever 6 away from the stop 29 about its pivot 10 the active end 11 is 20 brought into firm contact with the wire at a point intermediate the lug 7 and mandrel 13 causing an indenture to be made in the wire at this point. With the indenture made the lever 5 is moved about its pivot axis in the 25 path of a circle until that portion of the wire extended beyond the mandrel is bent back and upon itself and around the mandrel as indicated in Fig. 3. The desired eye or loop is thus formed. To adjust the mandrel 13 30 that wire of a different gage may be acted on it is only necessary that the ratchet 25 be moved and relocked with its second tooth in the position formerly occupied by the first. In doing this the active portion 14 of 35 the mandrel is lifted above its previous plane and the portion 15 moved to the position formerly occupied by the portion 14. The dogs 8 and 16 are then reversed or shifted, to bring their short ends into active service 40 whereupon the levers 6 and 5 are moved in sequence as before. The movement or adjustment of the mandrel causes the loop formed in the wire to be made larger and the movement or adjustment of the dogs is 45 such that larger wire can be fitted respectively between the abutment 7 and the dog 8 and mandrel 13 and dog 16.

The stop 29, although it may be of any form desired, is preferably of the form 50 shown. It is fastened as at 30 to the bed 1, extended to one side of the bed as at 28, bent at right angles to form the stop *per se*, and then continued or extended laterally to act as a guide beneath which the lever 6 is moved. 55 Should adjustment of the stop be required (and it will be if the dogs are shifted) this adjustment can be effected by simply loosening the fastening means 30, moving the stop about said fastening means as an axis and then retightening said means as before. The means for fastening the dog 16 to the lever 5 is indicated at 17, and is substantially the same as the fastening means 9 for the dog 8. 60 In the modification of Fig. 6 the lever 6 65 is pivoted as at 31 and has formed upon its

inner end a cam 32. This cam is so related to the dog 33 that the latter is moved through manipulation of the lever 6. The dog 33 is also provided with a cam 34 and a wire engaging surface 35 and is pivoted to the plate as at 36 for movement as indicated by dotted lines. When it is desired to bend the wire, the lever 6 is pulled in a counter-clockwise direction throwing the cam 32 against the adjacent face of the dog 33 75 whereby the latter is caused to move in a clockwise direction with the result that the end 35 of the dog is forced into engagement with the wire 19 in much the same manner as disclosed in connection with the preferred form of the device. The lever 6 and the dog 33 are held against return movement by friction. After indenting the wire by movement of the dog the lever 5 is carried through its cycle of operation to form the 80 loop in the wire. Two pins 37 and 38, if desired, may be used as stops to limit the movement of the lever 5 and in consequence spread the bent end of the wire away from the unbent portion thereof. 90

Although I have described more or less precise forms and details of construction, I do not intend to be understood as limiting myself thereto as I contemplate changes in form, the proportion of parts and the substitution of equivalents as circumstances may suggest or render expedient and without departing from the spirit of the invention as claimed. 95

What is claimed is: 100

1. In a wire bending machine, a bed plate, a mandrel, an abutment positioned at one side of the mandrel, a lever, an indenture-forming dog carried by the lever and movable with it to indent the wire at a point intermediate the abutment and the mandrel, a second lever movable about the mandrel as an axis, and a loop-forming dog carried by the second lever and movable with it in a circular path above the mandrel to bend the wire in loop form, the two levers subsequent to the formation of the loop lying closely adjacent and at opposite sides of the abutment. 110

2. In a wire bending machine, a bed plate, 115 a mandrel, a substantially wedged shaped abutment positioned at one side of the mandrel, the sharp end of the abutment pointing toward the mandrel, a pivoted lever, an indenture-forming dog carried by the lever 120 and movable with it to indent the wire at a point intermediate the abutment and the mandrel, a second lever movable about the mandrel as an axis, and a loop-forming dog carried by and movable with the second- 125 mentioned lever in a circular path about the mandrel for bending the wire in loop form, the two levers upon the formation of the loop lying closely adjacent and at opposite sides of the abutment with the wire extend- 130

ed respectively between the indenture-forming dog and the abutment and between the loop-forming dog and the abutment.

3. In a wire bending machine, a bed plate, 5 an abutment mounted thereon, a mandrel also mounted thereon, both the mandrel and abutment engaging the wire upon the same side although at different points, a lever, and a reversible indenture-forming dog carried by the lever and movable with the lever into and out of contact with the wire, said contact being at a point intermediate the mandrel and the abutment and upon the opposite side of the wire from that engaged 10 by the mandrel and the abutment that the indenture may be formed at the mentioned intermediate point.

4. In a wire bending machine, a bed plate, a substantially wedge-shaped abutment 20 mounted thereon for contact with the wire, an indenture-forming dog mounted at one side of the abutment to form with the abutment a wire holding means, a mandrel, and a former movable about the mandrel for 25 bending the wire in loop form around it, the free end of the wire, when bent, engag-

ing the opposite face of the abutment from that engaged by the unbent portion thereof.

5. In a wire bending machine, a bed plate, 30 an abutment mounted thereon, a mandrel also mounted thereon, both the mandrel and the abutment engaging the wire upon the same side thereof although at different points, a lever, a reversible indenture-forming dog carried by the lever and movable 35 into and out of contact with the wire, the contact being at a point intermediately of the mandrel and the abutment upon the opposite side of the wire from that engaged by the mandrel and abutment that the indenture may be formed at the mentioned intermediate point, a second lever, and a reversible dog carried by the second lever and movable with it in a circular path about the mandrel for bending the wire around it in 40 45 loop form, the relative arrangement of the reversible dogs being such that the space between them and the mandrel is variable to accommodate wires of different gage.

In testimony whereof I affix my signature. 50
